United States Patent Office

Des. 214,384
Patented June 10, 1969

214,384

TOY DOG OR THE LIKE

Reuben B. Klamer, 9460 Wilshire Blvd., Beverly Hills, Calif. 90212, and Robert Y. Allen and Melvin Shaw, Los Angeles, Calif.; said Allen and said Shaw assignors to said Klamer

Original design application July 13, 1967, Ser. No. 7,790. Divided and this application May 3, 1968, Ser. No. 11,764

Term of patent 14 years

Int. Cl. D21—02

U.S. Cl. D34—2

FIG. 1

FIG. 2

FIGURE 1 is a perspective view showing a toy dog or the like embodying our ornamental design, the opposite side is substantially a mirror image thereof; and

FIGURE 2 is an exploded side view thereof.

This application is a division of copending application Ser. No. D.7,790, filed July 13, 1967, now abandoned.

We claim:

The ornamental design for a toy dog or the like, substantially as shown and described.
